UNITED STATES PATENT OFFICE.

WILLIAM J. KLEIN, OF BUFFALO, NEW YORK.

BUTTON SWITCH.

Application filed July 21, 1924. Serial No. 727,258.

This invention relates to an improved button switch and seeks to provide a device of this character wherein the construction and mounting of the parts will, from the standpoint of feasibility of manufacture, be extremely simplified for thus rendering manufacture inexpensive while, at the same time, retaining entire efficiency of operation.

The invention further seeks to provide a device wherein the button actuated spring contact employed will have a wiping action against its coacting contact.

And the invention still further seeks to provide a device embodying a novel spring contact and associated terminals as well as a novel mounting for said parts.

Other and incidental objects will appear hereinafter.

In the drawings:—

20 Figure 1 is a sectional view through my improved button switch,

Figure 2 is a perspective view showing the parts disassembled but in proper relative position, and

25 Figure 3 is a transverse sectional view on the line 3—3 of Figure 1, looking in the direction indicated by the arrows.

In carrying the invention into effect, I employ a substantially hemi-spherical shell 10 having an annular base flange 11 at the periphery of which is an annular downturned lip 12. Axially the shell is pressed in as indicated at 13, and formed with a central opening, and slidable through said opening is a button 14. As best shown in Figure 1, the button comprises a sheet metal shell formed at its base with an annular flange and turned over said flange is a bottom plate 15 closing the shell, an annular shoulder 16 being thereby produced to engage the shell 10 for limiting the button in its outward movement through the shell.

In conjunction with the shell 10 I provide a cross plate 17 which is formed centrally with an oblong opening 18 and is pressed in from the upper side thereof at said opening to define an oblong frame 19 angle shaped in cross section. At the ends of the frame, the plate is offset to form arcuate shoulders 20 from which extend flanges 21 terminating in downturned lips 22. Fitting in the frame 19 of the cross plate 17 is an insulating strip 23. This strip may be of fiber or other approved insulating material and, as brought out in Figure 3, the side flanges of the frame are bent over against

the upper face of the strip, as indicated at 24, for binding the strip in the frame. At one end, the strip is, as brought out in Figure 2, provided with a notch 25 while at a point centrally thereof the strip is formed with a transversely disposed oblong slot 26. Near one end, the strip is further provided with an opening 27 at opposite sides of which are slots 28 while at its opposite end, adjacent the base of the notch 25, the strip is formed with an opening 29 like the opening 27 and slots 30 like the slots 28. Mounted upon the strip 23 at its lower side, is a sheet metal terminal 31 lying flat against the strip and bent at one end portion thereof to define an inclined contact 32 sloping downwardly beneath the slot 26 of the strip. Formed on the side edges of the terminal are lugs 33 which are received through the pair of slots 28 of the strip and, as shown in Figure 3, are bent over against the upper side of the strip for rigidly connecting the terminal therewith. Screwed through said terminal is a binding screw 34 accommodated in the opening 27 of the strip. Freely accommodated through the notch 25 of the strip is a spring contact 35 provided at one end with a lug 36 overlying the lower face of the strip. As brought out in Figure 1, the contact inclines toward its free end upwardly away from the upper face of the strip and is bent near its free extremity to form a downturned tongue 37 accommodated in the slot 26. Overlying the lug 36 of the contact is a sheet metal terminal 38 and formed on the side edges of said terminal are lugs 39 which are received through the slots 30 of the strip 23 and bent over against the upper side of said strip for rigidly connecting said terminal as well as the spring contact 35 with the strip. Screwed through the said terminal is a binding screw 40 which extends freely through the lug 36 of the spring contact and is accommodated in the opening 29 of the insulating strip.

Attention is now directed to the fact that the cross plate 17 as well as the terminals 31 and 38 and the spring contact 35 may all be struck or pressed from suitable sheet metal. These parts may accordingly be readily produced. Furthermore, by providing the terminals 31 and 38 with the lugs 33 and 39, these parts are secured to the insulating strip 23 without the use of separate fastening devices while also, the spring contact 35 is secured in position by the ter-

terminal 38. Preferably, the terminals and the spring contact are first mounted on the insulating strip 23 when the insulating strip is assembled upon the cross plate 17. The button 24 is then mounted upon the shell 10, when the cross plate is assembled upon the shell. As shown in Figure 1, the cross plate is of a length to extend diametrically of the shell, fitting therein, when the spring contact 35 is disposed to bear against the inner end of the button 14, yieldably holding the button at the limit of its outward movement upon the shell. As illustrated, the shoulders 20 of the cross plate 17 are disposed to extend within the shell fitting against the curved wall thereof so that the flanges 21 of the plate seat flat against the flange 11 of the shell while the lips 22 of the plate fit within the lip 12 of the shell abutting thereagainst. The flanges 21 of the plate are provided with openings 41 and punched from the flange 11 of the shell are eyelets 42 which extend through said openings and are upset against the flanges 21 for rigidly connecting the cross plate with the shell. As shown in Figure 1, the eyelets 42 are of a diameter to freely receive screws or other suitable fastening devices 43 securing the device upon a wall or other surface against which it is desired to mount the device.

The binding screws 34 and 40 are, of course, provided so that circuit wires may, as suggested in Figure 1, be connected with the terminals 31 and 38. Accordingly, as will be seen in view of the foregoing, the button 14 may be depressed for flexing the free end of the spring contact 35 through the slot 26 of the insulating strip 23 to engage the contact 32 and close a circuit through said contacts. As the spring contact 35 is thus flexed, the tongue 37 thereof will, as will be seen, ride over the inclined contact 32 with a wiping action so that the cooperating surfaces of the contacts will be maintained clean and bright.

Having thus described the invention, what I claim is:—

1. In an electric switch, the combination of an insulating strip having an opening, a contact extending at one side of the strip beneath said opening, and a spring contact fixed at one end upon the strip at said side thereof and shaped to extend at its free end at the opposite side of the strip over said opening, the free end of the spring contact

being movable through said opening to engage the former contact.

2. In an electric switch, the combination of an insulating strip having an opening, terminals mounted on the strip at one side thereof and having lugs extending through the strip and securing the terminals thereto, a contact carried by one of said terminals and extending beneath said opening at said side of the strip, and a spring contact secured by the other of said terminals at said side of the strip and extending at the opposite side of the strip over said opening, the free end of the spring contact being movable through said opening to engage the former contact.

3. In an electric switch, the combination of an insulating strip having an opening and provided with a notch at one end thereof, a contact fixed to the strip at one side thereof and extending beneath said opening, and a spring contact fixed to the strip at said side thereof and shaped to extend through said notch at the opposite side of the strip over said opening, the free end of the spring contact being movable through said opening to engage the former contact.

4. In an electric switch, the combination of a shell open at one end and having a radial base flange provided with a down-turned lip, an oblong apertured plate extending across the open end of the shell and offset to fit said flange and lip, means engaging the offsets of the plate and securing the plate to the shell, an insulating strip overlying the aperture in the plate and provided with an opening, fixed and movable contacts carried by the strip to extend at opposite sides thereof above and below said opening, and a button mounted upon the shell for flexing the movable contact through said opening to engage the fixed contact.

5. In an electric switch, the combination of a shell open at one end, a stationary insulating strip mounted in the open end of the shell and provided with an opening, contacts mounted on the lower side of the strip, one of said contacts extending beneath said opening and the other contact extending above the strip over said opening, and a push button carried by the shell for shifting the latter contact through said opening to engage the former contact.

In testimony whereof I affix my signature.

WILLIAM J. KLEIN. [L. S.]
